Patented Feb. 10, 1920.

UNITED STATES PATENT OFFICE.

JOSEPH MOKEN, OF NEWARK, NEW JERSEY.

CLOTHESPIN.

1,330,211.

Specification of Letters Patent. Patented Feb. 10, 1920.

Application filed May 13, 1919. Serial No. 296,824.

To all whom it may concern:

Be it known that I, JOSEPH MOKEN, a citizen of the United States, and a resident of Newark, county of Essex, and State of New Jersey, have invented certain new and useful Improvements in Clothespins, of which the following is a specification.

This invention relates to an improved clothespin that is used with facility, has a number of recesses that permit its being placed over a clothesline, the multiplicity of these recesses permitting the use of the clothespin after a number of the prongs or fingers have been damaged or broken, and also permit the use of the clothespin for joining pieces of fabric so that, if desired, a series of garments or pieces of goods can be suspended from one another, thus economizing on the clothesline necessary for the suspension of the goods.

The invention is illustrated in the accompanying drawing, in which Figure 1 is a side view of a clothespin made according to my invention. Fig. 2 is a bottom view of the clothespin illustrated in Fig. 1, and Fig. 3 is a cross-section showing the pin used for joining two pieces of fabric.

The clothespin is preferably made of wood and consists of a main or body portion 30 10, preferably cylindrical on the outside and provided with a series of fingers, one of which is a central finger and the other fingers are placed around it and spaced from the center finger and from each other.

In the form shown, the fingers 11, 12 and 13 are arranged in spaced relation around the central finger or pin 14, this being usually done by making the saw cuts 15, 16 and 17, these saw cuts providing the spaces 40 provided for the reception of the clothesline when a pin is placed over the line and pressed down, there being enough resiliency in the wood, as in the ordinary form of clothespin, to grasp the line. To facilitate the placing of the pin, the marginal or outer fingers 11, 12 and 13 are provided with beveled or rounded parts 18, thus making converging openings between the fingers and also between the fingers and the central 50 finger or pin 14.

The central finger is rounded or beveled, as at 19, merging the triangular cross-sectional shape toward the bottom into a chiseled end 20, although various and dif-

ferent shapes can be given to the lower 55 part of the central finger, as will be clearly understood.

The upper part of the clothespin is left plain or can be provided with a suitable grasping head or knob to provide for its 60 manipulation. The clothespin can be used in other ways than as an ordinary clothespin, inasmuch as it can be employed to join the ends, especially at the side edges, of two garments or sheets of fabric, so that, 65 if desired, one can be suspended from the other.

In Fig. 3 I show a sheet 21 and also a sheet 22, the ends of which are passed over around the central finger 14 and out through 70 openings that flank the opening opposite the point of the triangular post over which the ends of the fabric are passed. In this way there is enough binding action on the fabrics to cause them to be held together, and 75 I have found that when placed horizontally on the adjoining edges of two pieces of fabric, the lower one is held securely against accidental removal from the upper one.

The multiplicity of fingers permits the 80 use of the clothespin after one or two fingers have been broken, thereby permitting an economy, and the formation of the fingers at their ends permits a ready and easy 85 "finding" of the clothesline when the pin is placed on it.

It is evident that I may use a number of surrounding fingers spaced from each other and from the central finger, but I have illustrated and prefer a clothespin 90 with a central finger, triangular in cross-section, and surrounding fingers having a flat wall opposite to the corresponding wall of the central finger, this permitting a somewhat broad form of outer or surrounding 95 finger, giving it the necessary strength and, through its comparatively thin form, having the proper degree of resiliency.

I claim:

A clothespin comprising a central finger 100 triangular in cross-section, and an outside finger opposite each face of the central finger and spaced therefrom, the outside fingers being spaced from each other.

In testimony that I claim the foregoing, I 105 have hereto set my hand, this 10th day of May, 1919.

JOSEPH MOKEN.
